COMBINATION SCALE AND LEVEL

John J. Schwartz, St. Paul, Minn., assignor to
Brown & Bigelow, St. Paul, Minn.

Application May 28, 1957, Serial No. 46,388

Term of patent 14 years

(Cl. D52—1)

Fig. 1

Fig. 2

Fig. 3

Figure 1 is a front perspective view of a combination scale and level, showing my new design;

Figure 2 is a front elevational view thereof with the scale in retracted position; and

Figure 3 is an end elevational view thereof from the scale end.

The rear of the article is plain in appearance.

I claim:

The ornamental design for a combination scale and level, as shown and described.
